POWDER TOOL

Verl Vorhies, Climax, Colo.

Application April 12, 1938, Serial No. 201,651

4 Claims. (Cl. 86—22)

My invention relates to tools used in connection with blasting.

My object is to provide a tool which will enable the user to split fuses, crimp caps, and otherwise facilitate blasting operations. Other objects will appear as the description progresses.

Figure 1 represents a side view of the device open; Fig. 2, a side view showing the device closed and the blade in position to be used as a knife; and Fig. 3, a side view showing the device closed.

Although I show the preferred embodiment of my invention, I do not thereby limit myself to the precise form shown, but wish it understood that within the scope of what hereinafter is claimed, various changes in the precise details of construction may be made without departing from the spirit of the invention.

A pair of curved bars A and B are pivotally connected by a pivot P. The bar A has a handle 2 and a head portion 3. The bar B has a handle 4 and a head portion 5. A spring 6 is disposed between the handles 2—4 and held in place by studs 7—8 on the handles 2—4, respectively.

A blade holder 9 is provided with a journal 10 which is mounted in the head portion 3 and held rigid by a thumb screw 11. A removable blade 12 is disposed in the blade holder 9 and held in place by thumb screws 13—14. The blade holder 9 is also provided with transverse grooves 15—16.

The head portion 5 is provided with transverse grooves 17 and 18 which cooperate with grooves 15—16, respectively, to crimp caps. The head portion 5 is also provided with a fuse holding portion 31 and with fuse holding chambers 19—20—21 and a plunger chamber 22.

A plunger 23 is disposed in chamber 22 and a spring 24 is disposed around the plunger 23 and serves to hold the plunger 23 away from the channel 19. The plunger is operated against the spring by a wedge member 25 connected to the head portion 3 of the bar A. Caps 301 are disposed on the pointed ends of the handles 2—4 to protect the clothing when carried in the pocket.

When a fuse 26 is disposed in the chamber 21, and the handles 2—4 are squeezed towards each other, the fuse is split snake mouth style from the end. When a fuse is disposed in chamber 20, and the device closed, the fuse is split the side cut style, the blade 12 cutting just through the powder channel.

Normally the spring 24 holds the plunger 23 away from the chamber 19, but when the handles are squeezed towards each other the wedge member 25 forces the plunger 23 towards chamber 19

and against the fuse 27 snugly while the blade 12 splits the fuse.

If a fuse is laid in the transverse groove 31 in the head 5, the fuse can be trimmed squarely on the end. The blade holding member 9 may be swung to the position shown in Fig. 2 so that the blade can be used as a knife. The handles are pointed so as to be used to punch holes in powder for lacing the fuse and inserting the cap or primer.

I claim:

1. A tool of the class described comprising a pair of bars pivoted together, each bar having a head portion and a handle portion; a blade holder secured to the head portion of one bar; a blade mounted in said blade holder; fuse receiving chambers in the head portion of the other bar each fuse receiving chamber being adapted to hold a fuse in proper position to be cut by said blade; and a plunger in said last named head portion adapted to lock a fuse in one fuse receiving chamber; and means to actuate said plunger when said head portions are disposed adjacent one to the other.

2. A tool of the class described comprising a pair of bars pivoted together, each bar having a head portion and a handle portion; a blade holder pivotally mounted on the head portion of one bar; means to hold said blade holder rigid; a blade disposed in said blade holder; means to lock said blade in said blade holder; fuse receiving chambers in the head portion of the other bar each fuse receiving chamber being adapted to hold a fuse in proper position to be cut by said blade; and a plunger in said last named head portion adapted to lock a fuse in one fuse receiving chamber; and means to actuate said plunger when said portions are disposed adjacent one to the other.

3. A tool of the class described comprising a pair of bars pivoted together, each bar having a head portion and a handle portion; a blade holder secured to the head portion of one bar; a blade mounted in said blade holder; fuse receiving chambers in the head portion of the other bar each fuse receiving chamber being adapted to hold a fuse in proper position to be cut by said blade; a plunger in said last named head portion adapted to lock a fuse in one fuse receiving chamber, means to actuate said plunger when said head portions are disposed adjacent one to the other; and cap crimping channels in one head portion and corresponding cap crimping channels in said blade holder.

4. A tool of the class described comprising a

pair of bars pivoted together, each bar having a head portion and a handle portion; a blade holder pivotally mounted on the head portion of one bar; means to hold said blade holder rigid; a blade disposed in said blade holder; means to lock said blade in said blade holder; fuse receiving chambers in the head portion of the other bar each fuse receiving chamber being adapted to hold a fuse in proper position to be cut by said blade; a

plunger in said last named head portion adapted to lock a fuse in one fuse receiving chamber; means to actuate said plunger when said head portions are disposed adjacent one to the other; and cap crimping channels in one head portion and corresponding cap crimping channels in said blade holder.

VERL VORHIES.
